UNITED STATES PATENT OFFICE.

JOHN E. WHITE, OF TARENTUM, PENNSYLVANIA, ASSIGNOR TO WEST PENN STEEL COMPANY, OF BRACKENRIDGE, PENNSYLVANIA, A CORPORATION OF NEW JERSEY.

ANNEALING-FURNACE.

1,158,760.

Specification of Letters Patent.

Patented Nov. 2, 1915.

Application filed March 18, 1915. Serial No. 15,185.

To all whom it may concern:

Be it known that I, JOHN E. WHITE, a citizen of the United States, residing at Tarentum, in the county of Allegheny and State of Pennsylvania, have invented certain new and useful Improvements in Annealing-Furnaces, of which the following is a specification.

My invention relates to annealing furnaces, and has for its object to provide, in a furnace of this type, a construction adapted to embody a combustion chamber, an outer wall structure, an inner annealing box chamber, and a series of circulating passages, ports and flues for the products of combustion, whereby to utilize the heating action thereof in an accurate manner, and to control the distribution of the heat for the purpose of applying it as desired to the annealing box and its contents.

One preferred construction of the furnace is illustrated in the accompanying drawings, in which—

Figure 1 is a horizontal sectional view through the furnace, indicated by the section line I. I. of Fig. 2. Fig. 2 is a vertical longitudinal section, indicated by the line II. II. of Fig. 1. Fig. 3 is a transverse sectional view, indicated by the line III. III. of Fig. 2. Fig. 4 is a similar view, indicated by the line IV. IV. of Fig. 2.

The objects in view are to provide, within the main furnace structure, a partially protected chamber for the annealing box, and means for producing circulation of the gases as desired over the roof thereof downwardly across the end of said chamber, and also downwardly through said roof at each side, through damper-controlled ports and between the inner walls and the annealing box, the gases eventually passing downwardly through ports in the supporting bottom, and eventually to the stack or other outlet through damper-controlled openings.

Referring to the drawings, 2, 2, represent the main side walls of the furnace, the inner portion of which may be preferably of fire brick or other refractory material, said walls extending upwardly from the main foundation construction. Between said side walls 2 at the front of the furnace is the furnace chamber 3 of any suitable construction, provided with the usual grate bars, and

which may be fired by hand or by a suitable stoker, as desired.

Above the furnace chamber 3, the roof 4 extends backwardly in arch form, preferably straight for a short distance above the bridge wall 5, and then slopes downwardly by the portion 6, terminating at the rear end of the furnace, which is closed by any suitable door construction 7. Extending rearwardly from bridge wall 5 is an inner coping or roof 8, forming the covering of the inner annealing box chamber 9, into which the annealing box is introduced and positioned, as indicated in dotted lines in Fig. 2, and referred to by numeral 10 in Fig. 3.

The annealing box, which is of well-known construction, extends upwardly above and is supported, with its contents, upon a bottom 11 which rests by downwardly extending pedestals or cross ridges 12, upon the supporting floor 13 of the furnace. Said floor is preferably provided with longitudinal rectangular hollow supporting metallic bearings 14, embedded in the brick work of the floor, and flush with the upper surface thereof, whereby to prevent abrasion by the annealing box bottom.

Centrally of the furnace floor is a ridge or pier 15, on the same general level with the floor, at each side of which are depressed channels 16, 16, extending longitudinally throughout the length of the bottom. The object of these channels 16 is two fold. First to provide clearance openings and tracks 17, 17, upon which travels a carriage for introducing the annealing box into and taking it out of the furnace, but which is not any part of the present invention. The channels 16 also provide longitudinal circulating passages for the outgoing gases of combustion, which pass underneath the bottom 11 at each side, as indicated by the arrows, downwardly into said channel, and then inwardly by a series of ports 18, 18, to common central downwardly directed ports 19, leading to flues 20, which pass along underneath the furnace floor to the stack or any suitable outlet. Each of said flues 20 is provided with a controlling damper 21, by which the exhaust of gas through any particular flue may be controlled or shut off.

At each side of the arched roof 8, it is

provided with a series of downwardly directed ports 22, opening downwardly flush with the inner face of the main side walls 2, from the main gas circulating passage 23 between main roof 6 and inner roof 8. This passage, as shown, owing to the sloping arrangement of the main roof 6, gradually narrows in depth toward the rear end of the furnace, terminating in a narrowed arch-like opening 24 immediately above the rear terminal of roof 8. By this arrangement, the gases in combustion are spread laterally into a comparatively thin film, and pass therethrough downwardly over the rear end 15 of the annealing box, and outwardly through the rear ports 18 to ports 19 and flues 20, as already described.

The ports 22 serve to convey the gases downwardly along each side of the annealing box, said ports being preferably arranged to correspond in position with the ports 18, whereby the gas currents will pass directly downwardly and then underneath the annealing box bottom to the respective 25 outlet ports 18, and to the stack in the same manner.

Each port 22 is provided with a controlling damper 25 operable horizontally across the port through a suitable slideway opening in the main wall, as clearly shown, whereby each port may be accurately controlled and either partially or entirely opened or closed, whereby to accurately regulate the degree of circulation therethrough. 30 By this means, and with the controlling dampers 21, it will be readily seen that the circulation of the gases around the annealing box 10 may be very accurately regulated, so as to distribute the heat thereto as desired 35 to suit the conditions of the work. The circulation of the gases is thereby well adapted for the highest efficiency of their heating qualities, and any undue exposure or liability to over or under heating is completely 40 avoided. The annealing chamber may thus be kept at a uniform or any desired temperature through its entire interior, thereby greatly contributing to the successful operation of the furnace.

50 The construction, operation and advantages of the invention will be readily understood and appreciated from the foregoing description.

It will be understood that the construction, proportions, design or other details of the invention may be changed or varied by the skilled mechanic, but that all such are to be considered as within the scope of the following claims.

60 What I claim is:

1. An annealing furnace having a combustion chamber and a bridge wall, an outer main roof, an inner roof extending from the bridge wall toward the opposite end of the 65 furnace and between the side walls and pro-

vided at each side with circulation ports, and a supporting bottom provided with a series of outlet openings communicating downwardly with an off-take channel and upwardly through the bottom of the furnace 70 interior.

2. An annealing furnace having a combustion chamber and a bridge wall, an outer main roof sloping toward the opposite end, an inner horizontal roof extending 75 from the bridge wall along underneath the main roof and terminating inwardly of the end of the main roof providing a transverse gas port between its terminal and the main roof and having at each side a series of 80 downwardly directed gas circulation ports adjacent the side walls, and a supporting bottom provided with a series of outlet openings.

3. An annealing furnace having a combustion chamber and a bridge wall, an outer main roof, an inner roof extending from the bridge wall toward the opposite end of the furnace and between the side walls and provided at each side with circulation ports, 90 and a supporting bottom provided with longitudinal channels at each side of a central pier having inwardly and downwardly directed outlet openings.

4. An annealing furnace having a combustion chamber and a bridge wall, an outer main roof, an inner roof extending from the bridge wall toward the opposite end of the furnace and between the side walls and provided at each side with circulation ports, 100 and a supporting bottom provided with longitudinal channels at each side of a central pier having inwardly and downwardly directed outlet openings communicating with outlet ports leading to a stack. 105

5. An annealing furnace having a combustion chamber and a bridge wall, an outer main roof, an inner roof extending from the bridge wall toward the opposite end of the furnace and between the side walls and provided at each side with circulation ports, 110 and a supporting bottom provided with longitudinal channels at each side of a central pier having inwardly and downwardly directed outlet openings communicating with 115 outlet ports leading to a stack and provided with controlling dampers.

6. In an annealing furnace, the combination with the main side walls, roof and bridge wall providing a furnace chamber, 120 and a supporting bottom having a plurality of outlet ports leading to a stack or the like, of an inner roof extending rearwardly from the bridge wall for a portion of the length of the furnace terminating adjacent to the 125 main roof and providing an intervening transverse gas port, and having a series of downwardly directing gas circulation ports at each side adjacent to said wall, and means for carrying off the products of combustion. 130

7. In an annealing furnace, the combination with the main side walls, roof and bridge wall providing a furnace chamber, and a supporting bottom having a plurality 5 of outlet ports leading to a stack or the like, of an inner roof extending rearwardly from the bridge wall for a portion of the length of the furnace terminating adjacent to the main roof and providing an intervening 10 transverse gas port and having a series of downwardly directing gas circulation ports at each side adjacent to said wall, each provided with a controlling damper, and means for carrying off the products of combustion. 15
8. In an annealing furnace, the combination with the main side walls and furnace chamber inclosed thereby, of a bridge wall, an inner roof extending horizontally therefrom between the side walls having downwardly extending ports at each side and terminating inwardly beyond the other end of 20 the furnace, an outer roof sloping from the furnace chamber portion and providing a narrow transverse gas port between it and the end of the inner roof, an endmost door, 25 and a floor structure provided with

and a floor structure provided with depressed channels and outlet ports leading therefrom to a stack or the like.

9. In an annealing furnace, the combination with the main side walls and furnace 30 chamber inclosed thereby, of a bridge wall, an inner roof extending horizontally therefrom between the side walls having downwardly extending ports at each side and terminating inwardly beyond the other end of 35 the furnace, an outer roof sloping from the furnace chamber portion and providing a narrow transverse gas port between it and the end of the inner roof, an endmost door, 40 and a floor structure provided with depressed channels and outlet ports arranged in transverse alinement with said downwardly extending ports and leading from said channels to a stack or the like.

In testimony whereof I hereunto affix my 45 signature in the presence of two witnesses.

JOHN E. WHITE.
